UNITED STATES PATENT OFFICE.

LOUIS P. OAKLEY, OF CONNERSVILLE, INDIANA, ASSIGNOR TO P. H. & F. M. ROOTS COMPANY, OF CONNERSVILLE, INDIANA, A CORPORATION OF INDIANA.

FLASK GUIDE.

Application filed January 24, 1921. Serial No. 439,380.

To all whom it may concern:

Be it known that I, LOUIS P. OAKLEY, a citizen of the United States, residing at Connersville, in the county of Fayette and State of Indiana, have invented a certain new and useful Improvement in Flask Guides, of which the following is a full, clear, concise, and exact description, reference being had to the accompanying drawings, forming a part of this specification.

My invention relates to flask guides for molds. The general object of the invention is to prevent relative displacement of the mold flask sections in the casting operations.

I am aware that guides have before been devised which were capable of accomplishing this same general purpose, but these prior devices have invariably been of a complicated nature, or have required the use of tools in their manipulation, and have proved to be entirely impractical. A salient feature of my improved guide is its simplicity. It is easy to operate and may be manipulated without the use of tools.

Various other objects of my invention will appear in the following detailed description, in which reference is made to the accompanying drawing illustrating the invention.

In the drawing—

Figure 1 is an end elevation of that portion of a flask to which the improvement of my invention has been applied.

Figure 2 is a vertical cross section taken on the line 2—2 of Figure 1, looking in the direction indicated by the arrows, and

Figure 3 is a detail in perspective of the flask guide showing the same partially disassembled for the purpose of better illustration.

In the three views, the same reference numerals are used to indicate the same parts.

The mold illustrated consists of the conventional flask sections 5 and 6, which are made of wood, cast iron, or any other suitable material. The section 5 is customarily referred to in foundry practice as the "cope" and the section 6 as the "drag" of the mold. The cope carries a bracket 7, secured thereon by bolts 8—8. A fork or bifurcation 9 is provided on the bracket 7, movable between the tines of which is the head 10 of a guide pin 11. Depending from the head 10 is a tail piece 12 of slightly enlarged cross section, which forms with the head 10 shoulders 13. These shoulders engage the nether side

of the bifurcation 9. A transverse opening 14 is provided at the outer end of the head 10 of the guide pin through which a clamping wedge 15 passes. The wedge 15 has a retaining pin 16, in its reduced end, which effectually prevents removal thereof from the opening 14. When the wedge is driven inwardly to the position shown in Figure 1, the guide pin is securely held in the bracket in an obvious manner.

Secured by bolts 17 to the drag 6 is a second bracket 18 in the face of which is cut a V-shaped notch 19. This notch co-operates with the triangularly shaped tail piece 12 of the guide pin, thereby preventing accidental disalignment of the flask sections.

Any suitable material may be used in making the brackets and guide pin, although I prefer to make both of the said elements of cast iron, and the wedge 15 and retaining pin 16 of wrought iron. Furthermore, as will hereinafter more clearly appear, it is immaterial in what relation the brackets are secured upon the flask sections as the guide will operate practically as satisfactorily if the brackets are interchanged, so that the bracket 18 is secured to the cope 5 and the bracket 7 to the drag 6.

The device is best adapted for use in the following manner: After the counterpart impressions of the pattern have been produced in the sand in the cope and drag, it is, of course, important that when the metal is poured, the cope and drag shall assume the same relation as before, so that the finished casting will be a faithful reproduction of the pattern. In order to insure accurate alignment of the flask sections during the pouring operations, the guide pins, at the time the pattern is placed in the mold and the sand packed and rammed thereabout, are moved inwardly so that the tail pieces 12 engage in the notches 19. The wedges 15 are then given a blow to secure the guide pins to their respective brackets. Thereafter, when the cope is repeatedly removed from, and replaced upon, the drag, the same relation of the two is maintained. The tail piece 12 is preferably of such a length as will insure that the cope properly clears the pattern when it is lifted from the drag. With the construction illustrated, the guide pins serve to guide the cope just as accurately at entering the notches as when the cope and drag are close together, and it

will, of course, be apparent that the length of the tail pieces is variable as desired to suit given conditions, and the same may be changed without altering the brackets. The 5 guide pins with their clamping wedges inseparably linked thereto are separable from the flasks, and are standard as regards their being capable of use with other flasks, and are not kept with the flasks when the same 10 are kept in a flask yard. The guide pins are therefore not likely to become broken or damaged. There are many additional advantages which will of course more readily appear to mechanics skilled in foundry practice, and which it is believed unnecessary here to enumerate.

While I have described the details of the preferred embodiment of my invention, it is to be understood that I do not limit myself to these details of construction, but desire to cover all adaptations and modifications coming within the spirit and scope of the appended claim.

What I claim is:

25 The combination with a pair of flask

members, of a bracket secured to one of the members and provided with a laterally opening V-shaped notch, a second bracket secured to the other member and provided with a laterally elongated slot open at its 30 outer end and having flat vertical walls, a pin having a portion formed with flat sides adapted to bear against the walls of said slot and being laterally and vertically adjustable therein and having shoulders 35 respectively adapted to engage one edge of the respective walls and having an extension formed with a V-shaped face adapted to engage said notch, and a wedge secured to the pin and transversely movable relatively 40 thereto, the wedge being adapted to engage edges of said walls opposite the edges engaged by said shoulders and to clamp the pin against movement in said slot.

In witness whereof, I hereunto subscribe 45 my name this 19th day of January, 1921.

LOUIS P. OAKLEY.
